Filed Oct. 16, 1964, Ser. No. 32,207

Term of patent 14 years

(Cl. D34—5)

FIG. 1.

FIG. 4.

FIG. 2.

FIG. 5.

FIG. 3.

FIG. 2 is a top plan view thereof;

FIG. 3 is a front elevational view thereof;

FIG. 4 is an end elevational view taken from the right of FIG. 1; and

FIG. 5 is an end elevational view taken from the left of FIG. 1.

The dominant feature of my design resides in the non-metallic rear portion of the putter head, which is striped substantially as shown.

I claim:

The ornamental design for a putter head or similar article, substantially as shown and described.
